Primary Examiner — Barbara Fox(74) *Attorney, Agent, or Firm* — Patterson Thuente Christensen Pedersen, P.A.(57) **CLAIM**

The ornamental design for a window operator cover, as shown and described.

DESCRIPTION

FIG. 1 is a front perspective view of a window operator cover according to the invention;

FIG. 2 is a front elevation view of the window operator cover depicted in FIG. 1;

FIG. 3 is a top plan view of the window operator cover depicted in FIG. 1;

FIG. 4 is a left side elevation view of the window operator cover depicted in FIG. 1;

FIG. 5 is a right side elevation view of the window operator cover depicted in FIG. 1;

FIG. 6 is a bottom plan view of the window operator cover depicted in FIG. 1; and,

FIG. 7 is a rear elevation view of the window operator cover depicted in FIG. 1.

The portions of the window operator cover shown in broken lines form no part of the claimed design.
